METHOD OF AND MEANS FOR HEATING
FORGINGSGeorge Spatta, Buchanan, Mich., assignor to
Clark Equipment Company, Buchanan, Mich.,
a corporation of Michigan

Application January 13, 1930. Serial No. 420,596

10 Claims. (Cl. 263—8)

This invention relates to a method of and means for forging, and relates more particularly to a new and improved method of heating the blanks that are to be forged and delivering them 5 to the forging machine.

In my copending application, Serial No. 416,- 537 filed December 26, 1929, I disclosed a method of forming banjo type rear axle housing for automotive vehicles from a cylindrical blank of 10 seamless steel tubing, in which method the tubing is first slotted at its central portion, then the end portions are swaged to reduce their diameter and to lengthen them, and the blanks thus formed are then heated and the central portion 15 expanded to form the banjo housing.

The present invention relates particularly to an improved furnace for heating the central portion of the slotted blank prior to the expanding operation, and while the machine 20 disclosed is primarily intended for this purpose, the principles of the invention are obviously applicable to machines designed to heat blanks for other similar forging operations.

In carrying out the method of my above mentioned copending application, the shaping of the banjo section of the housing is performed in two steps, the first of which merely expands the central section, flattening it from a cylindrical section to a flat section, and the second 30 shaping and folding that flat section to form the banjo housing. In carrying out this method, I find it advantageous to perform most of the forging operation with a single heating of the metal, that is, the blanks are fed through a heating furnace and delivered therefrom to the forging machines which perform their functions sufficiently rapidly to enable both machines to operate on the blank before it has cooled to such an extent that it must be reheated. Although 40 the operation of the particular forging machines in question is fairly rapid, it is nevertheless necessary to arrange these machines so that the time lost in transferring the heated blanks from the furnace to the first machine and from the 45 first machine to the second machine can be reduced to a minimum.

In carrying out a preferred embodiment of my invention, I position the two machines with their operating fronts adjacent, and mount the heating furnace over one of the machines. The hot blanks delivered from this heating furnace are lowered by a rapidly operating gravity means conveyor, which drops the blank into a rack conveniently disposed between the two machines, 55 and slightly above the dies of these machines.

Two workmen operating the two machines, grab opposite ends of the hot blank and place it in the first machine, which is then operated to perform its step of the forging process. The blank is then raised from this machine, transferred under the rack of the conveyor to the other machine and placed in the die of that machine. The latter machine is then operated to complete the forging process, and the blank removed from the latter machine and sent on its 60 way to the next step in the process of the formation of an axle housing.

In order to insure that the two forging presses involved in this step of the process of manufacture are utilized to an economic extent, I have 70 timed the heating of the blanks so that there is a minimum delay between the successive operations of the machine.

To this end I have arranged the conveyor in heating arrangement so that another hot blank 75 will be delivered to the rack between the machines immediately after the finished blank has been removed from the second machine. This compels the workmen to work at a definite rate of speed, since if they lag behind the hot blanks 80 will arrive before they have completed their step in forging of the previous hot blank, and if they are sufficiently slow more than one blank will be piled into the rack of their machine. I 85 have found that by suitable arrangement of the speed of heating the blanks and the timing of their delivery to the forging machine, the men can perform the forging function in the allotted time throughout the entire day without undue fatigue, and that the forging machine and heating furnace are therefore efficiently used and the production of the arrangement is efficiently 90 accomplished.

The elevated furnace which I have placed over one of the forging machines comprises a rectangular steel casing suitably lined with a refractory material and provided with slots in its opposite sides through which the end sections of the blank are projected. A chain conveyor 100 is disposed on the outside of the furnace, this conveyor having two sections, one on each side of the furnace and in approximate alignment with the slot in the furnace.

The conveyor contains a plurality of hooks or other suitable projections which pick up the blanks from a loading platform and elevate them into the furnace and through it to its discharge end. The speed of travel of the conveyor is timed so that the blanks will be in the furnace 105 long enough to be heated to the proper forging 110

temperature, and the hooks on the chain are spaced so that the rapidity at which the blanks are delivered to the discharge end of the furnace is correct to allow the operators of the forging machine sufficient time to perform the forging operations on one blank before the next heated blank is delivered to them.

The heated blanks leave the conveyor at the discharge end of the furnace, and are picked up by an inclined runway which delivers them to a vertically disposed gravity conveyor that lowers them to the rack between the forging machines. This gravity conveyor may conveniently be a chain conveyor provided with hooks for engaging the blank, or any other suitable type of conveyor capable of lowering the blank to the receiving rack.

The furnace conveyor is power driven in any preferred manner, such as by an electric motor, and the vertical conveyor depends upon the weight of the blank disposed on one of its sides for its operation in lowering the blank.

While I have arranged the units of my invention in a particular manner to fit the invention to a particular set of manufacturing conditions, I am not to be limited to the specific details, since I am aware that the embodiment of the invention may be modified greatly to meet other manufacturing requirements.

Now to acquaint those skilled in the art with the teachings of my invention, reference is made to the accompanying drawings in which a preferred embodiment of it is shown by way of example and in which:

Figure 1 is a side elevational view, partly in section, showing the furnace, the furnace conveyor, the gravity conveyor, and the forging presses in outline;

Figure 2 is an elevational view taken along a longitudinal section through the furnace;

Figure 3 is a transverse section through the furnace taken along the line 3—3 of Figure 2; and

Figure 4 is a detailed view of the furnace conveyor chain and link thereon.

Referring to the drawings now in more detail, it will be seen that the arrangement includes forging presses 1 and 2, which are disposed with operating faces 3 and 4, respectively, adjacent to each other. The details of forging presses 1 and 2 are covered in my copending applications Serial No. 425,426, filed February 3, 1930, and Serial No. 426,545, filed February 7, 1930, to which cases reference is here made for those details.

The forging press 2 is operated first to perform the initial step in the expanding of the slotted blank to form a banjo housing, and the press 3 subsequently operated to finish the shaping of the expanded portion of the blank into the shape it occupies in the completed housing.

The furnace indicated generally at 5, is conveniently situated above and to the back side of the forging press 1, this arrangement being advantageous in that it saves floor space in the shop, and also in that it permits locating the furnace above the heads of the working men, so that the heat escaping from that furnace can be carried out of the shop to render the working conditions in the shop more comfortable.

A loading platform 6 is disposed at the extreme end of the framework 7 on which the furnace is supported, this platform 6 being inclined so that the blanks 8 placed thereon will roll naturally toward the conveyor chain of the

furnace. This conveyor chain 9 picks the blanks off of the loading platform 6 and elevates them to the slot 10 which runs in a general horizontal direction through the furnace 5 to the discharge end 11 of that furnace. The heated blanks pushed out of the discharge end of the furnace by the conveyor 9 roll down an inclined guideway 12 onto the hook 13 of the gravity conveyor 14, the weight of the blank causing the gravity conveyor to operate to lower the hook 13 to its lowermost position 15, in which position the blank falls from the conveyor onto the receiving rack 16.

The workmen pick the hot blank off the receiving rack 16, lower it over the dies of the press 2, operate that press, remove the blank therefrom and transfer it horizontally under the rack 16 to the press 3 and insert it in the dies of the latter press. In order that the space under the rack 16 may be kept clear, that rack is hung from the supporting framework 17 of the furnace in any preferred manner, as by the horizontal strut members 18.

The furnace comprises a steel shell 20 which is of generally rectangular shape and provided with a rectangular projection 21. This shell has an open top, and is lined with a suitable refractory material 22 which protects the shell 20 from the heat of the flames within the furnace. A cover 23 is formed in a similar manner, and lined with a similar refractory material 24. The cover is closed at the top and open at the bottom, and the refractory material 24 supported in it by flanges 25 which are riveted to the side walls 23 of the cover. The framework upon which the furnace is supported comprises vertical studs 7, 17 and 27, and suitable horizontal members 28 and 29 which fit beneath the casing 20 to support the furnace thereon.

The furnace cover is supported on these vertical members by flanges 30 and 31 riveted to the side walls of the cover and to the vertical members 27 and 17, respectively. The projection of the cover is supported by horizontal cross members 32 which are attached to the vertical stud 7 and its companion stud on the opposite side of the machine and positioned beneath the end of this extension.

In this manner, the furnace and cover are supported one above the other in such a manner that the slots between the adjacent edges of the members are free so that blanks may be rolled through it. The vertical studs 7, 17 and 27 are spaced sufficiently far apart so that the blank will travel endwise between them without striking against them.

Additional horizontal studs 33 and 34 extending from the front to the back side of the framework are provided to support a platform 35 upon which the driving mechanism for the conveyor 9 is located. This mechanism preferably comprises an electric motor which is connected to the conveyor 9 through a reduction gear, and since the arrangement is old and well understood by those skilled in the art it has been omitted from the drawings to avoid an unnecessary complication of the drawings. The platform 35 also serves as a foot rest for a workman who is lighting the fire in the furnace or adjusting the conveyor or furnace mechanism.

Conveyor 9 comprises a chain 37 which is threaded over sprocket wheels 38, 39, 40 and 41, these sprocket wheels being keyed to shafts 38', 39', 40' and 41' which are disposed transversely of the machine in suitable bearings, (not shown)

and which contain similar sprocket wheels located on the opposite or back side of the machine.

5 A plurality of recessed cleats 42 are attached to the link of the chain, and serve to pick up the blanks 8 and to propel them through the furnace.

10 Flanges 43 and 44 are attached to the casing 20 of the furnace and disposed in a horizontal position below the slots between that casing and the cover 23 of the furnace. The chain links 37 rub on the horizontal members of these flanges 43 and 44, and the cleats 42 of the chain are thereby disposed in a vertical position to push the blank 8 horizontally through the slot in the furnace. The end cylinders of the blank rest upon the edge of the casing and the blank rolls as it is pushed by the cleats. This insures uniform heating of the midsection of the blank.

20 This slot, as will be seen in Figures 2 and 3, is just wide enough to clear the end sections of the blanks 8, so that the escape of heat through the slot is minimized. This loss of heat is further reduced by an inwardly moving stream of 25 air drawn into the furnace through the slot to provide air of combustion to the burner, as will presently appear. The slot contains a curved section 45 located in juxtaposition to the sprocket wheel 38, through which section the direction of 30 the travel of the blank is changed from vertical to horizontal.

At the discharge end of the machine, when the blanks engage the inclined runway 12, they roll away from the cleats 42, so that as the 35 chain is moved around the sprocket wheel 38, these cleats may fall to a horizontal position, then to a vertical position which is essentially upside down from that which they occupy when driving the blanks through the furnace.

40 The furnace 5 may be heated by gas or oil, which is blown into the furnace through the pipe 46 under suitable pressure controlled by the valve 47 conveniently located at the end of the furnace underneath the projection 21.

45 By this arrangement, the central and slotted section of the blank can be heated to the proper forging temperature during the travel of the blank through the furnace and since the flames in the furnace are prevented from coming in direct contact with the end sections of the blank, those end sections are maintained relatively cool so that the cleats 42 and links 37 of the conveyor chain 9 are not damaged by being in contact with red or white hot metal. Furthermore, 55 the end sections are sufficiently cool that workmen who are protected with suitable leather or asbestos gripping pads can handle the blanks by grasping their end sections without the use of tongs.

60 The burned gases from the furnace are conducted out of the cover through a suitable flue 48 which is provided with dampers, (not shown) to regulate the draft through it. Air of combustion enters the furnace with the fuel, through 65 the ports 45, and through the transverse slots 10 along the sides of the furnace, and I have found that this arrangement economically heats the blanks to forging temperature. The heat employed is employed at a point well above 70 the heads of the workmen so that the temperature in which they must work is moderate and they can, therefore, maintain a more rapid pace without undue fatigue.

75 While I have chosen to show a particular embodiment of my invention, I have done so by way

of example only, as there are many modifications and adaptations which can be made by one skilled in the art without departing from the teachings of my invention.

Having thus compiled with the statutes and 80 shown and described a preferred embodiment of my invention, what I consider new and desire to have protected by Letters Patent is pointed out in the appended claims.

85 What is claimed is:

1. In a forging furnace, a steel casing having a generally rectangular portion having a horizontal projection extending from one end, a cover for said furnace registering therewith, means for supporting said cover over the furnace but spaced therefrom, the bottom edge of the cover and the top edge of the furnace together defining a path leading from the bottom of the projection upward and horizontally through the furnace, a refractory lining for the 90 furnace and cover, and a burner for heating the furnace.

2. In a forging furnace, a casing having a generally rectangular portion having a horizontal projection extending from one end, a 100 cover for said furnace registering therewith, means for supporting said cover over the furnace but spaced therefrom, the bottom edge of the cover and the top edge of the furnace together defining a path leading from the projection in- 105 to and through the furnace, a refractory lining for the furnace and cover, and means for heating the furnace.

3. Means for heating the midsections of axle 110 housing blanks or the like comprising, a furnace elevated above the height of an attendant and having a firebox embracing the central parts of the blanks only, the furnace having slots in the opposite walls thereof and the ends of the axle housing blanks extending out of the 115 furnace through said slots throughout the entire movement of the blanks through the furnace, a travelling conveyor engaging the outwardly extended ends of the blanks for carrying the blanks crosswise through said firebox 120 in spaced relation to each other, means for feeding blanks to the conveyor, a delivery rack below the furnace for holding the heated blanks in definite delivery position, and an automatically operated lowering device for quickly cover- 125 ing the heated blanks and placing them in the delivery rack when they emerge from the furnace.

4. Means for heating the midsections of generally cylindrical blanks comprising the combination of an elevated firebox embracing the midsections of the blanks, the ends of the blanks extending through the firebox, a rack upon which cold blanks are stored, a travelling conveyor embracing the outside of the firebox and 130 engaging the extended ends of the blanks for carrying the blanks from said rack up to and through said firebox, a trough leading from the firebox down which the heated blanks roll free of said conveyor, a receiving means, and an automatic lowering device for carrying the 135 heated blanks to said receiving means.

5. A forging furnace for heating the central sections of blanks comprising the combination 140 of a firebox located above the floor level and adapted to embrace only the central portions of the blanks, means in the firebox for heating the blanks, a rack disposed near the floor level for storing the cold blanks, a travelling conveyor having a vertically moving portion ad- 145 150

1 jacent said rack for removing the blanks there-
 2 from by engaging the ends of the same and a
 3 horizontal portion adjacent the firebox for
 4 moving the blanks therethrough, a second rack
 5 located near the floor level, and a gravity con-
 6veyor for receiving the heated blanks from said
 7 firebox and lowering the same to and dropping
 8 them upon said second rack.

10 6. A furnace for heating long blanks comprising the combination of a generally rec-
 11 tangular firebox having slots in its side walls defining a passageway through which project
 12 the ends of the blanks that are within the fire-
 13 box, conveyor means located entirely outside of
 14 said firebox in juxtaposition to said slots, a rack
 15 for holding blanks to be heated in said firebox,
 16 means on said conveyor means for carrying said
 17 blanks from said rack through said firebox,
 18 burner means in the firebox for heating the
 19 midsections of the blanks, a flue receiving the
 20 gases of combustion and drawing in air through
 21 said slots, means for removing the heated blanks
 22 from said conveyor, a second rack, and an inter-
 23 mittently movable device for rapidly moving
 24 said heated blanks from said removing means
 25 to said second rack.

26 7. In combination, a forging furnace for heat-
 27 ing the central sections of blanks to the forging
 28 temperature and including a heating chamber
 29 located above the floor level and having means
 30 therein for heating the blanks, a travelling con-
 31veyor having a vertically moving portion for
 32 receiving the blanks by engaging the ends of the
 33 same and having a horizontal portion embracing
 34 the heating chamber for moving the blanks
 35 therethrough, a receiving rack located near the
 36 floor level, and a gravity conveyor receiving the
 37 heated blanks from the heating chamber and
 38 lowering the same and depositing them on the
 39 receiving rack.

40 8. A furnace for heating metal blanks to the
 41 forging temperature, comprising a chamber of
 42 a width less than the length of the blanks and
 43 having upper and lower parts including side
 44 walls and separated by slots of a width slightly
 45 greater than the diameter of the outer portions
 46 of the blanks, the slots being in two opposite
 47 side walls of the furnace and being parallel to
 48 one another and continuous and open at their
 49 ends, with the space between the parallel slots
 50 free of obstructions, whereby a blank may be
 51 placed in the furnace with the ends thereof ex-
 52 tends out through the slots, and means on
 53 the outside of the furnace for engaging the out-
 54 wardly extending ends of the blank and advanc-
 55 ing said ends along the slots to move the blank
 56 through the furnace.

57 9. The method of heating the central portion
 58 of an axle housing to the forging temperature
 59 which comprises, placing the central portion of
 60 the housing into a furnace, advancing the central
 61 portion through the furnace while main-
 62 taining the ends of the housing outside of the
 63 furnace and, throughout the heating of the
 64 housing, maintaining a movement of air into
 65 the furnace from the region of the outwardly
 66 extending ends of the housing.

67 10. The method of heating the central portion
 68 of an axle housing to the forging tempera-
 69 ture which comprises, placing the central portion
 70 of the housing into a furnace, introducing
 71 fuel and some air of combustion into the fur-
 72 nace, advancing the central portion of the hous-
 73 ing through the furnace while maintaining the
 74 ends of the housing outside of the furnace and,
 75 throughout the heating of the housing, main-
 76 taining a movement of additional air of com-
 77 bustion into the furnace from the region of the
 78 outwardly extending ends of the housing.
